HUMIDIFIER

Milton Perlman, Detroit, Mich.

Application March 21, 1950, Serial No. 150,880

3 Claims. (Cl. 261—119)

1

This invention relates to humidifiers and in particular to automatically refillable humidifiers for use in either gravity or forced hot air heating systems and the like.

In the prior art, many and various types of humidifiers have been employed in hot air heating systems, sometimes located in the plenum chamber of the hot air furnace and sometimes mounted in the main duct leading from the furnace. In either event, it has been usual to employ a pan into which water from a constant water source is maintained at an established level responsive to valve means. The valve means is usually complicated and expensive to manufacture, install and maintain, and generally is composed of a float operated water valve requiring rather minute adjustment and which becomes inoperative readily due to corrosion or the presence of foreign matter in the float chamber and around the valve seat.

With the foregoing in view, the primary object of the invention is to provide an inexpensive to manufacture, simple, easily installed and trouble-free humidifier for gravity or forced hot air heating systems employing a self-cleaning gravity operated valve operable directly responsive to the pressure head of water supplied to the humidifier and the weight of water contained in the humidifier.

Other objects of the invention will become apparent by reference to the following detailed description taken in connection with the accompanying drawings, in which:

Fig. 1 is a longitudinal vertical sectional view of a humidifier embodying the invention mounted on and through the wall of a hot air furnace or an air duct leading from a hot air furnace, the reservoir of the humidifier being filled with water and the intake valve closed.

Fig. 2 is a horizontal view taken substantially on the line 2—2 of Fig. 1.

Fig. 3 is a longitudinal sectional view similar to Fig. 1 except that most of the water in the reservoir of the humidifier has evaporated, the reservoir has tilted forward, the valve is open, and the reservoir is being filled with water simultaneously with cleaning foreign substance from the valve seat.

Fig. 4 is an enlarged plan view of a trunnion or pivotal support for the humidifier reservoir.

Fig. 5 is a sectional view taken on the line 5—5 of Fig. 4.

Fig. 6 is an enlarged fragmentary sectional view showing the valve construction and splash shield preferably employed.

Fig. 7 is an enlarged sectional view taken on the line 7—7 of Fig. 1 showing one type of adjustable valve nozzle support that may be employed.

2

the line 7—7 of Fig. 1 showing one type of adjustable valve nozzle support that may be employed.

Fig. 8 is an enlarged plan view of one type of adjustable stop that may be employed to limit the forward tilting of the humidifier reservoir.

Fig. 9 is an enlarged sectional view taken on the line 9—9 of Fig. 2 showing balancing weights that may be employed to balance the reservoir to compensate for variations in water pressure in the water supply to the humidifier.

Referring now to the drawings wherein like numerals refer to like and corresponding parts throughout the several views, the particular humidifier disclosed for the purpose of illustrating the invention comprises, in general, a mounting plate 10 having an aperture 100 therein secured by such means as self-tapping screws 11 to a hot air furnace or duct wall 12 over an aperture 120 therein with the aperture 100 in the mounting plate 10 disposed in registry with the aperture 120 in the hot air furnace or duct wall 12, a pair of inwardly disposed brackets 13 secured by such means as self-tapping screws 14 or by welding or riveting to the rear of the said mounting plate 10, the said brackets 13 each having a cradle 15 formed at the inner end thereof, a reservoir pan 16 preferably deep or having a large water capacity at its rear rectangular end 160 and shallow or of small water capacity at its front narrow end 161, trunnions 17 fixed to each side of the said reservoir pan 16 intermediate its ends by means of which the said reservoir pan 16 is pivotally supported on the said brackets 13 and in the said cradles 15 which constitutes a fulcrum point at the inner ends thereof, the said reservoir being balanced about the said trunnions 17 to pivot downwardly at its front narrow end 161 when substantially or relatively empty and upwardly at its front narrow end 161 when substantially or relatively full, the forward narrow small capacity end 161 of the reservoir 16 extending out through the aperture 100 in the mounting plate 10 and the aperture 120 in the furnace or duct wall 12, a cylindrical well 18 formed in the bottom of the forward narrow end 161 of the reservoir 16, a resilient preferably neoprene valve seat or nozzle seal or stopper 19 disposed in the said well 18, a water supply nozzle or valve seat 20 fixed by means of a bracket 21 in adjustable depending relationship onto the front of the mounting plate 10 and disposed over the said seal or stopper 19, a continuous water supply 22 connected to the said nozzle 20, a splash shield 23 disposed over the said nozzle 20, the

said valve seal or stopper 19 and nozzle or valve

seat 20 serving as or constituting valve means to admit water from the water supply 22 to the reservoir pan 16 when the forward, shallow, or small capacity end of the reservoir 16 is less than full to substantially empty and tilted downwardly about its trunnions 17 or pivot points by the pressure of water from the water supply nozzle 20, and to shut off water from the water supply 22 when the reservoir 16 is sufficiently full to tilt its rear, deep, or large capacity end downwardly so that the forward end tilts upwardly about its trunnions 17 to close the valve means, an adjustable stop 24 extending between the brackets 13 limiting the downward tilting of the forward end of the reservoir 16, the said reservoir 16 having an overflow aperture 25 in the front and near the top thereof, and a cover 26 having a drain aperture 27 therein disposed over the forward end of the reservoir 16, the aperture 100 in the mounting plate 10 and the water supply nozzle 20, the said cover 26 being secured to the mounting plate 10 by suitable self-tapping screws 28.

The mounting plate 10 is preferably formed of sheet metal and is crimped around its periphery at 30 for strength and to accommodate the flange 31 of the inwardly disposed brackets 13. The said inwardly disposed brackets 13 may be of any desired shape or construction to pivotally support the reservoir 16 thereon. However, by employing the cradles 15 formed in the top of the brackets 13 and the trunnions 17, the reservoir 16 rocks and turns on its trunnions 17 in the cradles 15 thereby eliminating a great majority of friction that might retard the tilting of the reservoir 16.

The reservoir 16 is preferably rectangular in shape at its rear end 160 and tapers to a narrow shallow front end 161 as best shown in Figs. 1 and 2. The trunnions 17 by means of which the reservoir 16 is pivotally or rockably supported in the cradles 15 of the brackets 13 are so located in the sides of the reservoir 16 as to cause the reservoir 16 to pivot or rock downwardly in front when empty or substantially empty and upwardly in front when full or substantially full. Each trunnion may comprise a bolt 32 extending outwardly from a side of the reservoir 16 onto which is telescoped a trunnion spool 33, a washer 34 and a lock washer 35. A nut 36 on the bolt 32 tightens the trunnion assembly 17 to the reservoir 16. As viewed in Figs. 4 and 5, the trunnion spool 33 rides in the cradle 15 formed in the top of the inwardly disposed brackets 13. Obviously, other types of construction and means for pivoting the reservoir 16 with respect to the brackets 13 may be employed.

The adjustable stop 24 likewise may be of any suitable construction. In the showing in the drawings, the adjustable stop 24 is formed of a rod 24 reduced in diameter and threaded at each end at 37 forming a shoulder 38 against which a washer 39 is positioned which abuts against the inside of a bracket 13 when the reduced threaded ends 37 of the said adjustable stop 24 are positioned in the horizontal slots 40 provided in each bracket 13. A washer 41 is positioned on the reduced threaded ends 37 of the adjustable stop 24, and, when the nuts 42 are turned up tightly, the adjustable stop 24 is anchored in its adjusted position in the slots 40 of the brackets 13, see Figs. 2 and 8. By adjusting the stop 24 forwardly or rearwardly in the slots 40, more or less forward tilt of the reservoir 16 is permitted when the said reservoir 16 is empty or substantially empty and is being filled, see Fig. 3.

By referring particularly to Figs. 1 and 7, it will be observed that the nozzle bracket 21 may

comprise an angle 45 welded or otherwise secured to the mounting plate 10 and an anchor plate 46 secured to the angle 45 by means of bolts 47. The angle 45 and anchor plate 46 are complementarily formed to engage and anchor the water supply nozzle 20 in a vertically adjusted position with respect to the neoprene nozzle seal 19, the preferred adjusted position of the nozzle 20 being such as will maintain the reservoir 16 substantially level when filled and the nozzle 20 sealed closed by the nozzle seal 19 as shown in Figs. 1 and 6.

The water supply nozzle 20 is preferably cylindrical in shape, is tapered at its lower end to a relatively small diameter or point 48, and has a water supply aperture 49 therethrough. The upper end of the nozzle 20 is preferably provided with a sleeve nut 50 which serves as a tube anchorage which connects the end of the continuous water supply line 22 to the said nozzle 20. The said nozzle 20 may be provided with a pair of spaced upper and lower annular bosses 51 and 52. The upper boss 51 prevents the nozzle 20 from sliding downwardly out of the bracket 21 before it is tightened, and the lower boss 52 serves as a hanger for the splash shield 23 preferably formed of molded rubber. The said splash shield 23 is of sufficient length and is the proper shape to prevent water being supplied to the reservoir 16 from the water supply nozzle 20 from splashing off the nozzle seal 19 and out of the reservoir 16.

The nozzle seal 19 which is preferably formed of neoprene, rubber or the like is sufficiently resilient to seal the water supply aperture 49 at the pointed end 48 of the water supply nozzle 20 whereby to prevent water from being supplied to the reservoir therefrom responsive to the tilting of the front narrow end 161 of the reservoir 16 upwardly when the reservoir 16 is substantially filled as indicated in Figs. 1 and 6. When the reservoir 16 becomes nearly empty from evaporation of water therein as indicated in Fig. 3, the front narrow end 161 thereof tilts downwardly and water is supplied thereto through the water supply line 22 and the water supply nozzle 20. As the reservoir 16 is being filled, water from the water supply nozzle 20 jets onto the nozzle seal 19 and cleans any accumulation of foreign matter from the top of the said nozzle seal 19 thereby assuring perfect seating of the end 48 of the water supply nozzle 20 onto the nozzle seal 19 when the front narrow end 161 of the reservoir 16 again tilts upwardly as the said reservoir 16 becomes substantially filled.

Not shown, but generally employed in humidifier installations, is a water supply shut-off valve of a type that permits regulation of the water supply volume and pressure in the water supply line 22, by means of which any excess force of the jet from the water supply nozzle 20 may be eliminated. If a pressure regulating valve is not employed in the water supply line 22, then, for the purpose of balancing the reservoir 16 against the pressure of water supplied thereto through the nozzle 20, a plurality of weights 60 may be employed, the said weights 60 being hooked over the side of the reservoir 16 by means of a hook 61 welded or otherwise secured thereto. By sliding the weights 60 along the side of the reservoir 16, the balance thereof about its trunnions 17 may be adjusted to compensate for variations in the reaction of water supplied to the reservoir 16 from the nozzle 20 arising due to local variations of the water pressure in the water supply line 22.

Although but a single embodiment of the invention has been shown and described in detail, it is obvious that many changes may be made in the size, shape, arrangement and detail of the various elements of the invention to accommodate it to various manufacturing and installation conditions, all without departing from the spirit and scope of the invention as defined by the appended claims.

I claim:

1. A humidifying device for imparting moisture to air by evaporation comprising a cradle constituting a fulcrum point, a reservoir pan pivotally mounted intermediate its ends on said cradle so as to constitute a lever in itself and so as to position said pan with a relatively large water containing capacity on one side of its pivot point on said cradle and a relatively small water containing capacity on the other side of its pivot point on said cradle so that said pan is leverwise biased when containing water, a water valve positioned adjacent the small water capacity end of said pan adapted to introduce water under pressure into said pan; said valve comprising a seal on the small water capacity end of said pan and a nozzle or seat separately fixed adjacent the small water capacity end of said pan; said valve being operated to open and close by pivoting said pan on said cradle; said pan being so positioned on said cradle so that when a desired predetermined level of water exists in said pan, the weight of the water in the large water capacity end of said pan so overbalances the weight of the water in the small water capacity end of said pan and the water pressure of said nozzle to pivot said pan on said cradle to close said valve, and so that when less than a desired level of water exists in said pan, the weight of the water in the large water capacity end of the pan does not so overbalance the weight of the water in the small water capacity end of said pan and the water pressure of said nozzle so that water is introduced into said pan.

2. A humidifying device for imparting moisture to air by evaporation comprising a cradle constituting a fulcrum point, a reservoir pan pivotally mounted intermediate its ends on said cradle so as to constitute a lever in itself and so as to position said pan with a relatively large water containing capacity on one side of its fulcrum point on said cradle and a relatively small water containing capacity on the other side of its fulcrum point on said cradle so that said pan is itself leverwise biased when containing water, an apertured water valve seat mounted adjacent

said pan adapted to introduce water under pressure into said pan, a valve stopper on said pan adapted to seal said apertured seat by pivoting said pan on said cradle to prevent water being introduced into said pan; said pan being so positioned on said cradle that when a desired predetermined level of water exists in said pan, the weight of the water in the large capacity end of said pan overbalances the weight of the water in the small capacity end of said pan and the water pressure of said seat to pivot said pan on said cradle to sealably press said valve stopper against said valve seat to prevent water being introduced into said pan while the condition exists.

15 3. A humidifying device for imparting moisture to hot air heating systems air by evaporation mountable in an element thereof in the path of hot air therethrough comprising a cradle constituting a pivot point, a reservoir pivotally mounted intermediate its ends on said cradle so as to tilt and so as to position said reservoir with a relatively deep end on one side of its pivot point on said cradle and a relatively shallow end on the other side of its pivot point on said cradle so that said reservoir itself forceable tilts when containing water, a water nozzle positioned adjacent the shallow end of said reservoir adapted to introduce water under pressure into said reservoir, and a seal on the shallow end of said reservoir adapted to seal said nozzle when pressed thereagainst by pivoting said reservoir on said cradle to prevent water being introduced into said reservoir; said reservoir being so positioned on said cradle that when a desired predetermined level of water exists in said reservoir, the weight of the water in the deep end of said reservoir overbalances the weight of the water in the shallow end of said reservoir and the water pressure of said nozzle to pivot said reservoir on said cradle to sealably press said seal against said nozzle to prevent introduction of water thereinto while the condition exists.
